UNITED STATES PATENT OFFICE.

EDWARD GOTTHEIL, OF GALVESTON, TEXAS.

IMPROVEMENT IN COTTON-GINS.

Specification forming part of Letters Patent No. 23,679, dated April 19, 1859.

To all whom it may concern:

Be it known that I, EDWD. GOTTHEIL, of Galveston, in the county of Galveston and State of Texas, have invented a new and useful Improvement in Cotton-Gins; and I do hereby declare that the following is a full, clear, and exact description thereof, reference being had to the accompanying drawings, through letters of reference marked thereon, forming part of this specification, in which—

Figure 1 represents a front elevation of my machine; Fig. 2, a side elevation; Fig. 3, a top view or plan, and Fig. 4 a vertical section taken on the line $x x$ of Figs. 1 and 3.

My invention has reference to that class of cotton-gins used for ginning the long staple or Sea Island cotton, and whereby the cotton is ginned without injury to the staple, and the lint is freed from motes and all other impurities.

To enable others to make and use my invention, I will proceed to describe its construction and operation.

A A represent two uprights of the framing of suitable form and construction to support all the working parts of the machine, which consists of a pair of polished steel rollers, b , one above the other, in close proximity, which are geared together by a pair of small spur-wheels at one end, by which they are rotated with equal velocity. Above and below these rollers are guards or dividing-plates c , to prevent any blast or current of air passing through from the rear side of the machine. On the rear side of these rollers, parallel with them and one above the other, are two cylindrical brush-rollers, d , so arranged that the upper one brushes the upper roller, and the other the lower one, while the brushes of each, when revolving, interlock between those of the other. The upper brush-roller is somewhat larger than the lower one, consequently its periphery travels at a greater velocity, revolving in the direction indicated by the arrows, and while they clean the rollers b they also receive the lint that passes between them, and the upper one, by the increased velocity of its periphery, gathers it off the lower one, and carries it to the comb e , whence it is discharged over the incline f into a receiver by the action of a blast of air issuing from the tube z above and below said comb. These hollow brush-

cylinders rotate on a short tubular journal, r , made stationary in the frame A, one end of which enters the cylinder on which the brushes are mounted, and the other end is connected by flexible tube p or otherwise with the fan-chamber. The opposite ends of these brush-cylinders have solid journals supported in the frame A, geared together, and rotated by suitable spur-wheels, y , leading and taking motion from the axle of the upper roller, b , on whose axle also is a band-wheel, s , by which the whole machinery is driven.

The endless belt table or apron G consists of a series of straps or webbing encompassing the rollers h and i , and is put in motion by a cord or strap around the pulleys h' and i' . On this apron is spread the cotton to be ginned, and by which it is conveyed toward the rollers onto a wire bed or grating, k , which is supported at its upper end in slots in the frame A, and at its lower end on two eccentrics, t , one on each end of the cam-shaft u , which rotates in the capped ends of the arms v , and which communicates to this bed k a motion to and from the rollers b , its upper edge sliding in the slot in the frame, also a rising and falling of the lower edge, which assists in feeding in the fiber and freeing the seed therefrom. Above this wire bed is arranged a tube, l , supported in adjustable bearings a , and having a slot or series of holes along one side, through which a blast of air is made to issue in such direction that it drives the cotton forward to the rollers. The fibrous portion being introduced by it between them, is drawn in and the seed forced off. It being too large to be held by the rollers is loosed from the fiber by the vibrating comb m , which is operated by a cam, w , on the shaft u , rotated by a spur-wheel, x , gearing into one on the end of the upper roller, b , and the seed drops through onto the chute n and thence to a receiver beneath, while the revolving cylindrical brushes d take the lint from the other side of the rollers, as before described. These brush cylinders or rollers each consist of a series of two or more longitudinal brushes (usually four) mounted on a hollow cylinder or tube, which is slotted longitudinally to within about an inch of each end between each row of the brushes, which are set a little distance apart, the spaces between said brushes corresponding with and

forming continuations of the slots in the tube on which they are mounted, and are held together in this position by a narrow band driven onto each end, so that when necessary these bands may be driven back and the brushes removed to be cleaned or renewed.

During the operation of ginning, while the lint passes from the rollers *b* to the brush-cylinders *d*, and thence to the comb *e*, it is subjected to a continuous and powerful blast issuing from the slots between the brushes, which removes all the motes and other impurities from the fiber, and discharges them through the wire grating *g* in their rear, so that when the lint is blown from the comb *e* into the receiver it is thoroughly cleaned as well as ginned. The blast for these purposes is obtained from a fan, *o*, or other suitable device erected in a convenient position contiguous to the machine, and is conducted to the several parts through flexible or other tubes, *p p'*.

The advantages of this gin over all others are, first, in the regularity of the feed. The material being kept up to the rollers by a blast of air is more regularly supplied than it could possibly be by hand, in which manner it is often pushed in in matted masses, whereas in this the fiber of the cotton, being the lightest, is first blown to the rollers, and by them drawn through, leaving the seed behind, instead of mashing and grinding a considerable portion of it. Secondly, in the continual cleansing of the rollers by the revolving brushes working against them to prevent the accumulation of any oily or gummy extract from the cotton bolls or seed, and in the regular and perfect

manner in which the cotton is taken by the brush-rollers when drawn from the seed; and, thirdly, in the perfect manner in which it is freed from motes and other impurities by the blast from the brush-rollers, thus performing the operations of ginning and cleaning by the same machine at one and the same time.

Having thus fully described my machine, what I claim therein as new, and desire to secure by Letters Patent, is—

1. The method of feeding the cotton-bolls to the rollers *b* by means of a blast issuing from a slotted or perforated tube or its equivalent, substantially as herein set forth.

2. I do not claim creating a blast of air to issue from the periphery of the brush-cylinders by means of wings within them by their own velocity, but I claim the arrangement of the two cylindrical brushes *d*, in combination with the rollers *b*, when the former are so constructed that a blast from an independent source may be forced through slots or perforations in their peripheries, substantially as and for the purposes set forth.

3. The comb *e*, in combination with the blast-pipe *z* for gathering the lint off the upper brush-roller and discharging it into its receptacle in the manner set forth.

In testimony whereof I have hereunto set my hand, before two subscribing witnesses, this 26th day of March, A. D. 1859.

EDWARD GOTTHEIL.
